UNITED STATES PATENT OFFICE.

CHARLES FROESCH, OF NEW YORK, N. Y., ASSIGNOR TO INTERNATIONAL MOTOR COMPANY, OF NEW YORK, N. Y., A CORPORATION OF DELAWARE.

WINDOW CONSTRUCTION.

Original application filed September 5, 1924; Serial No. 736,009. Divided and this application filed November 12, 1926. Serial No. 147,923.

This application is a division of application Serial No. 736,009 of Charles Froesch filed September 5, 1924.

The present invention relates to window constructions, adapted particularly for use in vehicles and moving bodies, where the motion thereof causes a vibration and irregular movement of the window frame. An object of the invention is to provide a window structure of the above type which affords an easy adjustment of the position of the window and a securing means which positively, yet yieldingly, secures the window in a desired position.

15 A further object is to provide a structure which will permit the window to be raised to a fully opened position where it is necessary to cut down the head room so that the movement of the window to such position is not 20 in the plane of the side of the body.

A still further object is to provide cushioning elements which enable the window to be secured in position without noise or rattle. These and other objects will appear in the 25 following description of the invention taken in connection with the accompanying drawings wherein:—

Figure 1 is a section taken in a transverse plane of a vehicle body showing in detail a window casement and sash according to the 30 present invention.

Figure 2 is a fragmentary view showing a portion of the window casement and structure whereby it is assembled.

35 Figure 3 is a section taken on line 3—3 of Figure 2 and looking in the direction of the arrows.

In the drawings *a* represents the side of a body, for example, a bus body having an 40 outer shell *a'* and an inner shell *a''* running continuously from the lower edge of the body upon one side of the vehicle to the corresponding edge upon the opposite side of the vehicle. These shells are secured together by suitable spacing strips or connecting elements in any desired manner.

Conveniently placed in these vertical sides are window openings *a³*. These openings are formed by cutting out suitable apertures in the shells *a'*, *a''* and fitting therein suitable pressed metal window casements. The casements may comprise a suitable window sill portion *h* formed of pressed metal and preferably welded to the shells *a'*, *a''*

and inner side frame members *h'* welded 55 on the one hand to the inner side of the shell *a''* and on the other hand to a pressed metal channel *h²*. A pressed metal outer frame member *h³* is adapted to be secured outwardly of the shell *a'* and to form with the channel *h²* a recess for the reception of a block *i* of yielding non-metallic material which is preferably recessed upon opposite sides to form a bar of material having the cross section of a dumb-bell and adapted to engage through plate *l* with a roller *j* carried on the window sash indicated in general at *m*. The roller *j* is adapted to travel in a guide formed by a pressed metal angle *h*, one arm of which is welded to the channel *h²* and the other arm of which is welded to the inner frame member *h'*, while the other side of the guide is formed by an angle *l* 60 slid 65 in a transverse direction with respect to the outer frame member *h³* and adapted to be maintained yieldingly against the roller by means of the rubber cushion *i*.

The inner window frame member *h'* may be grooved as at *h⁴* to receive a strip of yielding non-metallic material *n* engaging 70 the end of the window sash *m* and yieldingly pressing the window outwardly to maintain the roller always against the guide *l*. Guide *l* is recessed at intervals as at *l'* for the reception of the roller *j* whereby the 75 window may be retained at predetermined points partially open to the desired degree. Guides *l* and *m* are turned inwardly at the 80 upper end of the window opening as at *L*, *K*, and serve to receive the sash when 85 in fully open position, a strip of yielding non-metallic material *o* being retained by suitable retaining member *o'* at the upper 90 end of the guide portion *L* to engage the top edge of the sash and yieldingly maintain it in open position, the lower edge of the sash resting then in the recess *l²* in the guide *l*. The top of the window is closed by a 95 bent metal frame member *p* formed with a recess *p'* for the reception of a rubber cushion element adapted to engage the upper end 100 of the sash to prevent rattling when in closed position. To receive the end of the sash in closed position for convenience in assembly the top frame member may be formed in two 105 pieces, an inner top member *p²* being welded to the inner shell *a''* as will be clearly apparent from an inspection of Figure 3 and so

formed as to provide a clearance for the upper end of the sash in opening and closing the window. As a re-enforcing element and to serve as an enclosure for the sash in fully open position a plate q of pressed metal may be secured to the top portion of the inner shell a^2 at its upper end and to the vertical portion of the inner shell member at its lower end, an opening q' being formed in the lowest portion thereof for the reception of the handle m' of the sash.

It will be seen that the construction described herein provides a window which may be moved to any desired position and which is secured against rattling in such position. The cushion elements are easily installed and the entire structure may be assembled with great facility.

Although a specific form of the invention has been shown herein, it is not to be interpreted as being limited by such disclosure, save as defined in the appended claims.

What I claim is:

1. In an adjustable window, a casement, a sash, tracks comprising fixed strips and movable strips carried with the casement, yielding non-metallic material interposed between the casement and the movable strips, rollers on the sash and positioned between the fixed and movable strips, removable face plates on the casement, and means to secure the plates in telescoping position with respect to the movable strip to confine the yielding material between the plates and movable strips under compression, whereby movement of the sash is yieldingly resisted.
2. In an adjustable window, a casement, a sash, tracks comprising fixed strips and movable strips carried with the casement, a flange on each movable strip, yielding non-metallic material engaging the movable strips, rollers on the sash and positioned between the fixed and movable strips, face plates on the casement, a flange on each plate and overlapping with the flange on the movable strips, and means to secure the plate in position to confine the yielding material between the plates and movable strips under compression, whereby movement of the sash is yieldingly resisted.

3. In an adjustable window, a pressed metal casement provided with inturned flanges, fixed guides formed on the casement sides, movable guides carried with the casement and opposed to the fixed guides, one wall of each movable guide overlapping co-operating inturned flanges carried with the casement, a sash, rollers carried with the sash and positioned between the fixed and movable guides, yielding non-metallic material disposed between the overlapped members, said non-metallic material being mounted under compression to yieldingly resist movement of the rollers.

4. In an adjustable window, a casement,

tracks comprising fixed and movable portions carried with the casement, extensions to the tracks at an angle to the casement, a sash having extensions mounted between the fixed and movable portions of the tracks, yielding non-metallic material interposed between the casement and the movable portions of the tracks, said yielding non-metallic material being maintained under a degree of compression, whereby movement of the sash is yieldingly resisted, and yielding non-metallic means at the end of the extensions to engage the top of the window when the sash is lifted to a wide open position.

5. In an adjustable window, a casement, tracks comprising opposed fixed and movable portions carried with the casement, yielding non-metallic material interposed between the casement and the movable portions of the tracks, said yielding non-metallic material being maintained under a degree of compression, a sash, rollers on the sash and positioned within the tracks, and yielding non-metallic means on the casement and engaging the sash on the side opposite to the movable portions, whereby the roller is normally urged against the movable portions and away from the fixed portions.

6. In a vehicle window, a casement between the inner and outer sides of the vehicle body, a recessed portion formed on the inner side of the top of the vehicle body adjacent the top of the casement to permit the top of the window sash to be moved inwardly, said recessed portion comprising a plate secured to the inner side of the body and having side portions, tracks on the casement, and means to permit the top of the sash to be raised in a plane at an angle to the casement comprising extensions to the tracks on the side portions of the plate.

7. In a vehicle window, a casement, tracks comprising fixed and movable portions formed thereon, yielding non-metallic material on the casement adjacent the fixed portions of the tracks, a sash, rollers on the sash, yielding non-metallic material on the casement and engaging the movable portions of the tracks, and yielding non-metallic means at the top of the casement to engage the outer side of the sash and hold the sash in position when the window is fully opened, said first-named yielding non-metallic material engaging the sash and tending to force the rollers into engagement with the movable portions against the action of the yielding non-metallic material in engagement therewith, whereby movement of the sash is yieldingly resisted.

8. In an adjustable window, a casement, tracks comprising fixed and movable portions carried with the casement, extensions to the tracks at an angle to the casement, a sash having extensions mounted between the fixed and movable portions of the tracks,

yielding non-metallic material interposed between the casement and the movable portions of the tracks to yieldingly resist movement of the sash, and means to hold the sash in fully opened position.

9. In an adjustable window, a casement, tracks comprising fixed and movable portions carried with the casement, extensions to the tracks at an angle to the casement, a sash having extensions mounted between the fixed and movable portions of the tracks, yielding non-metallic material interposed between the casement and the movable portions of the tracks to yieldingly resist movement of the sash, and means on the tracks and at the ends of the extensions thereof to hold the sash in fully opened position.

10. In an adjustable window, a casement, tracks comprising fixed and movable portions carried with the casement, extensions to the tracks at an angle to the casement, a sash having extensions mounted between the fixed and movable portions of the tracks.

yielding non-metallic material interposed between the casement and the movable portions of the tracks to yieldingly resist movement of the sash, and means on the tracks to hold the sash in partly opened position.

11. In an adjustable window, a casement, tracks comprising fixed and movable portions carried with the casement, extensions to the tracks at an angle to the casement, a sash having extensions mounted between the fixed and movable portions of the tracks, yielding non-metallic material interposed between the casement and the movable portions of the tracks to yieldingly resist movement of the sash, means on the tracks to hold the sash in partly opened position, and means on the tracks and at the ends of the extensions thereof to hold the sash in fully opened position.

This specification signed this 9th day of November, A. D. 1926.

CHARLES FROESCH.
